UNITED STATES PATENT OFFICE

2,386,663

EDGE SCRAPER FOR ELECTROLYTIC
TINNING LINES AND THE LIKERobert S. Deans, Pittsburgh, Pa., assignor to
Carnegie-Illinois Steel Corporation, a corpora-
tion of New Jersey

Application November 16, 1944, Serial No. 563,787

6 Claims. (Cl. 15—3)

My invention relates to improvements in edge scrapers for electrolytic tinning lines and the like.

In the production of bright electrolytic tin plate, the deposited tin is melted, as for example by resistance heating of the plated strip. Since heavier plating occurs at the edges of the strip, the same requires more heat than is necessary for the body of the strip in order to flow the coating, resulting in the latter attaining an excessive temperature. Also, such heavier plating deposit may be too great due to the presence of treed formation along the strip edges.

My invention contemplates providing means for removing the excess plating metal from the strip edges by the application of self-adjusting cutters to said edges, applied with equal and uniform pressure without injuring the desired bonded layer of plating metal thereon.

I also have in view, the positive removal of the metal cuttings from the strip so that the same will not interfere with subsequent processing.

Additional objects and advantages will become apparent from the following description taken in connection with the accompanying drawings wherein:

Fig. 1 is an elevational view showing the application of my invention to an electrolytic tinning line or the like;

Fig. 2 is a sectional view thereof taken on the line II—II of Fig. 1;

Fig. 3 is an elevational view of one of the scrapers and its mounting; and

Fig. 4 is a sectional view taken on the line IV—IV of Fig. 3.

Referring to the drawings, the strip 1 coming from the plating tank (not shown), in an electrolytic tin line or the like generally has an excessive plating metal deposit along its edges irregularly projecting laterally from the strip. This crystalline treed formation is loose and for an interval after its formation is relatively soft or wet. My improved scraper is applied to the strip edges while the excess plating metal is in the aforesaid condition, and in order that said metal may be removed before the strip is further processed, as for example, by melting the plated coating.

For the purpose of mounting the scraping apparatus, a channel base 2 is supported transversely beneath the horizontal pass line of the strip, and supports spaced tracks 3 located transversely adjacent the loci of the strip edges, said tracks having recessed longitudinal rails 4 for the wheels 5 of scraper carriages 6. In addition, carriages 6 are provided with depending central projections 7 slidably received in coacting guides 8

mounted on the tracks, as particularly shown in Fig. 4.

Each carriage 6 is powered by a weight 9 connected to the carriages by a cable 10, the latter being disposed over suitable guide pulleys 11, whereby the carriages are urged toward the edges of the strip 1, as particularly shown in Fig. 2. Tie-back or stop cables 12 may be provided in order to limit the travel of the carriages and to 10 retract the same when necessary.

Each carriage mounts a scraper wheel 13 of hardened steel, freely rotatable in an adjustable bifurcated horizontal support 14 secured to a bracket 15 on the carriage by means of a bolt 16. Said scraper wheels are preferably mounted in a substantially erect position transversely of the strip with their peripheries in contact with the strip edges, and with the centers thereof slightly above the plane of said strip to effect rotation of the wheel by tangential components of the pressure between the wheels and strip.

The scraper wheels 13 are thus rotated in a direction downwardly toward the upper surface of the strip, tending to discharge the scraped metal downwardly within box-like collectors 17 substantially enclosing the wheels, and particularly the lower portions thereof, said collectors having discharge chutes 18 depending through the carriages and through slots 19 in the tracks 3 and base 2. A common hopper 20 is disposed beneath and supported from the base 2 to receive the metal scrapings from the chutes 18 for ultimate disposal of said scrapings. The side walls of the collectors 17 are cut away at 21 for passage of the strip therethrough in contact with the wheels 13.

In order to remove small particles of metal, air nozzles 22 are mounted on air lines 23 and directed upon the edges of the strip 1 toward the wheels 13 so as to blow said particles into the collectors 17.

In order to increase the rotative travel of the scraper wheels 13, the same may be slightly canted or inclined as indicated in dotted lines in Fig. 4, by adjustment of the support 14 upon its bolt 16. The weights 9 are of sufficient size to urge the carriages so that the pressure of the cutters 13 will just be sufficient to remove the granular crystalline treed formation from the strip edges, without cutting or injuring the latter and so as to leave the bonded tin coating or layer thereon.

It will therefore be seen that I have provided a scraping apparatus which will ride or follow the strip without restricting lateral movement of the latter, and which will at all times exert an

equal cutting pressure upon the strip edges. The permitted travel of the carriages 6 upon their tracks will permit of use of the scraping device upon strips of different widths. Also, the action of the scrapers and the air nozzles removes the cuttings from the strip so as not to interfere with subsequent operations, as for example, during the melting treatment of the tin plate.

Various changes and modifications are contemplated within the scope of the following claims.

I claim:

1. An edge scraper for electrolytic tinning lines and the like wherein the tin plate is conveyed and processed in strip form, including a carriage mounted for movement transversely of the strip, a scraper wheel freely rotatable on the carriage and positioned for rotation by peripheral contact thereof with the moving edge of the strip, and means actuating the carriage for maintaining the scraper wheel in contact with the said strip edge under substantially constant pressure.

2. An edge scraper for electrolytic tinning lines and the like wherein the tin plate is conveyed and processed in strip form, including a carriage mounted for movement transversely of the strip, a scraper wheel freely rotatable on the carriage and positioned for rotation by peripheral contact thereof with the moving edge of the strip, means actuating the carriage for maintaining the scraper wheel in contact with the said strip edge under substantially constant pressure, and a collector substantially enclosing the scraper wheel for receiving the scrapings therefrom.

3. An edge scraper for electrolytic tinning lines and the like wherein the tin plate is conveyed and processed in strip form, including a carriage mounted for movement transversely of the strip, a scraper wheel support on the carriage, a scraper wheel freely rotatable in said support and positioned thereby in peripheral contact with an edge of the strip, the region of contact of said strip and wheel being below the center of the latter, and means actuating the carriage for maintaining the scraper wheel in

contact with said strip edge under substantially constant pressure.

4. An edge scraper for electrolytic tinning lines and the like wherein the tin plate is conveyed and processed in strip form, including a carriage mounted for movement transversely of the strip, a scraper wheel support on the carriage, a scraper wheel freely rotatable in said support, said support positioning the scraper wheel transversely of the strip edge in peripheral contact therewith and being adjustable to incline said wheel in relation to the plane of said edge, and means actuating the carriage for maintaining the scraper wheel in contact with said strip edge under substantially constant pressure.

5. An edge scraper for electrolytic tinning lines and the like wherein the tin plate is conveyed and processed in strip form, including a carriage mounted for movement transversely of the strip, a scraper wheel support on the carriage, a scraper wheel freely rotatable in said support, said support positioning the scraper wheel transversely of the strip edge in peripheral contact therewith and being adjustable to incline said wheel in relation to the plane of said edge, the region of contact of said strip and wheel being below the center of the latter, and means actuating the carriage for maintaining the scraper wheel in contact with said strip edge under substantially constant pressure.

6. An edge scraper for electrolytic tinning lines and the like wherein the tin plate is conveyed and processed in strip form, including a base positioned transversely of the strip, carriages movable thereon adjacent the loci of the strip edges, scraper wheels freely rotatable on the carriages in substantially erect position and in peripheral contact with the edges of the strip, the regions of contact of said strip edges and the wheels being below the centers of the latter, means for urging the carriages toward the strip for engagement of the wheels with said strip edges under substantially constant pressure, and collectors mounted on the carriages substantially enclosing the scraper wheels for receiving the scrapings therefrom.

ROBERT S. DEANS.
